UNITED STATES PATENT OFFICE.

EMIL L. CLAUS AND WALTER E. CLAUS, OF MILWAUKEE, WISCONSIN.

OVEN HEAT-CONTROL DEVICE.

Application filed May 25, 1921. Serial No. 472,610.

To all whom it may concern:

Be it known that we, EMIL L. CLAUS and WALTER E. CLAUS, both citizens of the United States, and residents of Milwaukee, in the county of Milwaukee and State of Wisconsin, have invented certain new and useful Improvements in Oven Heat-Control Devices; and we do hereby declare that the following is a full, clear, and exact description thereof.

This invention relates to certain new and useful improvements in oven heat controlling devices, in which a bimetallic strip is held substantially rigid at each end and has a valve member medially connected therewith whereby the resultant bowing of the member under temperature changes actuates the valve member and controls the oven heat.

In the oven heat controlling or regulating devices now generally employed there is some leakage of gas from the valve proper where the valve stem passes outwardly therefrom, as the result of which the underwriter's approval is not as readily obtained and furthermore there is a resulting waste in fuel. It is hence an object of this invention to provide improved means for insuring the positive prevention of leakage past the valve member stem and the leading off of all gas which may tend to escape, to be consumed by a pilot light.

In all thermostatic instruments it is essential that some play be allowed when the parts thereof are cool in order to accommodate for the expansion of the parts when under heat, and consequently the present oven heat controlling devices have been incapable of fine adjustment due to this slack being engaged by one side of the adjusting member when the temperature adjustment is being lowered and another side when the temperature is being raised resulting in a variation of a number of degrees. Consequently it will be readily seen that with the slack, which is absolutely necessary, it is impossible to obtain exact calibration and it is therefore another object of this invention to provide means whereby a tension is applied at all times to the necessary slack so that in adjusting either to or from a set position the adjustment will be made exact.

Another objection to a thermostatic controlling device employing a bi-metallic member made substantially rigid at both ends and connected at an intermediate point with a valve member is, that should the operator

desire to advance the oven heat at first, say 550 degrees, and then later adjust the device for a lower temperature, 300 degrees, some compensating means must be connected with the bi-metallic member, as under the great heat the same is bowed and the adjustment to a lower temperature will draw in the member and seat the valve and a continued adjustment will bend the member in an opposite direction. This applied extra stress to the bi-metallic member, while under heat, is very liable to strain the same so that it will not resume its normal position when cool.

Consequently it is a further object of this invention to provide means engageable with one fastening or securing member of the bi-metallic member whereby the same will give when the stress of adjusting the device nears the point where injury would be done the bi-metallic member.

It is still a further object of our invention to provide an improved heat regulating or controlling device of the class described, which is capable of ready application to ovens now in use as well as to ovens at the time of their manufacture without in any manner marring the same and without necessitating any change whatsoever in the parts thereof.

With the above and other objects in view which will appear as the description proceeds, our invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, we have illustrated one complete example of the physical embodiment of our invention constructed according to the best mode we have so far devised for the practical application of the principles thereof, and in which: Figure 1 is a perspective view looking at one side of an oven equipped with our invention;

Figure 2 is a top plan view of our improved device, the oven wall being in section and parts of the device being broken away and in section;

Figure 3 is a view part in section, part in elevation taken through the controlling member on the line 3—3 of Figure 1.

Figure 4 is a fragmentary view of one end of the thermostatic member and its support,

5 Figure 5 is a fragmentary view of the opposite end of the thermostatic member and its adjustable securing member, the thermostatic member being in section, and

10 Figure 6 is a fragmentary view, partly in elevation and partly in section, illustrating the relative areas of the pilot supply pipe inlet and outlet.

15 Referring now more particularly to the accompanying drawings in which like numerals designate like parts throughout the several views, the numeral 5 designates the heating oven of a range or stove, the burner of which (not shown) is supplied with fuel by a pipe 6. The fuel for the burner passes through our improved control device which is connected with the pipe 6 by a connection 20 7 and with a burner by a connection 8. The connection 7 has a shut-off valve or cock 9 therein from which also leads a pilot supply pipe 10, the pilot supply pipe opening 11' in valve 9 being adjustable by a screw 11.

25 The area of the opening 11' communicating with the pilot supply pipe is preferably less than that of the outlet 10', where the pilot is maintained, whereby the pressure within pipe 10 is atmospheric for the reasons hereinafter set forth.

30 The control device consists of a valve casing or body 12, which may be either in the form of an L (as shown) or a straight coupling provided with an inlet 13 with which connection 7 is coupled and an outlet 14 with which connection 8 is coupled. The inlet and outlet are separated by a partition within the valve casing which is centrally bored or apertured to provide a 35 fuel passage-way or port 15 formed with a valve seat 16. One wall of the body 12 is bored concentric with the valve seat 16 and is internally threaded to receive a cap or plug 17.

40 45 The valve member 18 is adapted to engage seat 16 and has a stem 19 which passes outwardly through a bore 20 in cap 17. The stem 19 has a substantially snug but slideable fit in bore 20 whereby to eliminate as much as possible all leakage from the interior of the valve casing around said stem. However, in order to prevent the escapage of any gas whatsoever into the interior of the oven past the valve stem, the bore 20 50 is medially recessed or counterbored to provide a pocket or intermediate chamber 21 in which such leakage expands. The plug 17 has its outer wall annularly grooved as at 22 in register with the pocket 21, with which it is connected by a plurality of passages 23. The casing 12 has an outlet 24 communicating with the groove 22 and from which leads a pipe or hollow wire 25 which is connected with the pilot supply pipe 10 55 60 65 the outlet 24 or pipe 25 forming means for

conducting any leaking fluid from the pocket.

Any fluid leaking from the interior of the valve casing around the stem 19 expands in the pocket 21, then escapes through 70 passages 23 into the chamber or channel 22 and then through pipe 25 into the pilot supply pipe 10 where the leakage is economically used in supplying fuel to the pilot (not shown). Back pressure in pipe 25 is 75 prevented by reason of the pilot opening 10' being of greater area than the inlet opening 11' to thus maintain the pressure within pipe 10 equal to or lower than atmospheric pressure, as hereinbefore described. 80

That portion of body 12 surrounding the bore in which plug 17 is secured is laterally flanged, as at 26, to provide means for attaching the device to the oven wall 5'. In attaching the device, the oven wall 5' is 85 cut away as at 27 at the point where it is desired to locate the device, and the valve body 12 is clamped to the wall by fastening members 28 which pass through apertures in the flange 26, through apertures in wall 90 5' and through a bracket member or supporting plate 29, a plate 30 being secured between the wall 5' and the flange 26 to serve as a filler and to carry the setting dial 31 to be hereinafter described. 95

The bracket member or supporting plate 29 is provided with two laterally extending diametrically opposed arms 32 and 33, the arm 32 having a lug or projection 34 formed at its outer end and the arm 33 a 100 centrally bored lug or projection 35 which projects in an opposite direction to lug 34, and is positioned exteriorly of the oven wall 5' through an opening therein. The lug 35 has its end positioned outwardly of the oven 105 away from the influence of the heat internally threaded to receive a setting screw 36. The extreme inner end of the setting screw 36 is cut away or reduced as at 37, to permit the attachment thereto of one end of 110 a strip of material 38 which is sensitive to temperature changes, screw 36 providing means for setting and adjusting strip 38. The other end of said strip is secured to projection 40 by the means now about to be 115 described.

The lug or projection 34 is centrally apertured as at 39 in alignment with registering apertures in the oven wall 5' and plate 30 to receive the stem 40 of a spindle formed 120 with an enlarged head 41 which overlaps the adjacent end of strip 38. The spindle 40 normally secures the end of the material engaged thereby firm against the projection 34 by means of a cone-shaped spiral spring 125 42 coiled about the outer ends of the stem 40 and confined between the plate 30 and a removable nut 43. The strip 38 is retained in engagement with head 41 by two spaced ears or guide means 44 between which the 130

adjacent strip end is positioned, this construction providing compensating means which come into play more especially when the oven is at a high heat and the operator 5 resets the device for a considerably lower temperature, as will hereinafter be set forth.

The strip of material 38 is preferably formed of two layers of metal of different degrees of expansibility, fused, welded, or 10 otherwise secured together so that when both ends of the strip are substantially rigidly held, the same will be bowed when subjected to heat due to one metal comprising the same expanding more than the other. 15 The bracket member 29 is centrally apertured as at 45 to accommodate the head of cap 17 and the inner end 46 of the valve stem 19 is threaded and passes into the interior of the oven through said aperture. The member 38 is provided with a central aperture 47 through which the valve stem end 46 passes and said member is adjustably made fast to the stem by knurled nuts 48 engaging the opposite sides of the strip. By this 25 construction, flexing or bending of strip 38, due to the expanding thereof as hereinbefore stated, will transmit a corresponding movement to the valve 18, however slight.

In the present embodiment the side of the 30 stem 38, formed of the material having the greater degree of expansibility, is placed nearest the oven wall of 5' so that, upon expansion, the medial portion of said member will be bowed theretoward to move the 35 valve toward seating position, however, it will be readily appreciated that this action may be reversed according to the design of the control valve.

In all thermostatic instruments it is necessary that some slack or play be allowed when the parts are cool in order that, when subjected to heat, the parts will not become bound, due to unequal expansion. Consequently, it will be readily appreciated that 45 the point of connection between the strip 38 and the setting screw 36, as well as any other connection, is preferably substantially loose, and, as a result, in setting the instrument as will be hereinafter described, this slack is on one side when setting the instrument for a higher degree of temperature, and on the other side when setting the instrument for a lower degree of temperature. As a result of this, accurate calibration is impossible 55 and we overcome this serious fault by a cone-shaped spring 49 coiled about the stem 19 and confined between the inner most nut 48 and the plug 17. The spring 49 at all times tends to urge the inner most nut 48 against the inner face of the strip 38 thus providing a tension which retains the slack or play always to one side of the parts, irrespective of the manner in which they are being adjusted.

60 As often times it is desirable to retain a

low flame at the burner, a set screw 50 is adjustably secured in an internally threaded bore 51 of the valve casing and has its inner end positioned concentric with respect to the valve seat 16. The bore 51 is surrounded by a boss 52 normally enclosed by a removable cap 53. As will be readily apparent the set screw 50 may be adjusted to permit full seating of the valve 18 or to prevent the seating thereof to any desired 70 degree. The plate 30 has its end 54 apertured to register with the aperture through which the projection 35 of the bracket member passes and is provided with a laterally projected flange, (not shown) to which the dial 31 is secured by fastenings 55, the dial 31 preferably being inclined at a substantially 45 degree angle with respect to the perpendicular to permit reading thereof. The dial 31 is provided with suitable graduations or various degrees of temperature and carries a medially pivoted pointer or indicator 56 which is connected with a collar 57, adjustably secured to the setting screw 36.

With the oven cold, and the thermostatic 90 member substantially straight, handle 58 is rotated to register indicator 56 with the temperature at which it is desired to maintain the oven and the greater the heat desired the further into the oven is positioned that end 95 of member 38 connected with screw 36. As the oven temperature increases, the medial portion of member 38 bows inwardly, by reason of that side thereof formed of the metal having the highest coefficient of expansion being nearest the oven wall, and valve 18 is consequently moved toward closed position.

When the oven has reached the desired 105 temperature, valve 18 abuts stop 50 and only a minimum flame is maintained at the burner, and as the oven temperature falls below the set degree, member 38 straightens, opening valve 18 to increase the flame of the burner.

Should the operator set the oven for a high temperature and then, after strip 38 is considerably bowed, set the oven for a lower temperature, the compensating means hereinbefore illustrated prevents straining of strip 38, should screw 36 be moved outwardly sufficient to engage valve 18 with stop 50 and unnaturally bend the thermostatic member.

What we claim is:

1. In a thermo-control device, a member 120 sensitive to temperature changes, means securing said member whereby the same will bow when heated, valve means connected with said member and carried thereby toward closed position when said member is heated and toward open position when said member cools, means for setting said member, and compensating means whereby straining of said member in setting is prevented.

2. In a thermo-control device, a member sensitive to temperature changes, means securing opposite end portions of said member, the means securing one end portion being transversely yieldable upon stress on said member reaching a predetermined limit, and a heat controlling member connected with said first mentioned member. 5
3. In a thermo-control device of the class described, a supporting plate, a member sensitive to temperature changes, means securing the ends of said member to said plate against longitudinal movement, one end thereof being transversely yieldable under excessive stress, and means connecting said member with a temperature controlling device. 10
4. In a thermo-control device of the class described, a supporting plate, a member sensitive to temperature changes, means securing the end portions of said member to the plate, one end thereof being transversely yieldable under excessive stress and the other end thereof being adjustable, and means connecting said member with a temperature controlling device. 15
5. In a thermo-control device of the class described, a supporting plate, a member sensitive to temperature changes, means normally rigidly securing one end of said member to the plate, said means being transversely yieldable upon the stress on said member reaching a predetermined limit, and means connecting the medial portion of said member with a temperature controlling device. 20
6. In a thermo-control device of the class described, a supporting plate, a member sensitive to temperature changes, means securing one end of said member to said plate, guide means engageable with the other end of said member, and securing means engageable with the other end of said plate and permitting transverse movement thereof upon the stress on said member reaching a predetermined limit. 25
7. In a thermo-control device, a member sensitive to temperature changes, means securing said member whereby the same will bow when subjected to a temperature change, said securing means preferably having some play to accommodate for the expansion of the member when subjected to heat, a heat controlling member, and a connection between said members, said connection including tension means for at all times taking up the play between the parts. 30
8. In a thermo-control device, a member sensitive to temperature changes, means securing said member whereby the same will bow when subjected to a temperature change, said securing means preferably having slight play to accommodate for the expansion of the parts when subjected to heat, a heat controlling member directly connected with said 35
- first mentioned member at an intermediate point, means for adjusting the actuation of said heat controlling member by said first mentioned member, and means for at all times applying a tension to one side of said first mentioned member to accommodate the play between the parts. 70
9. In a device of the class described, a valve casing, a valve seat in said casing in axial alinement with an opening in said casing, a centrally bored plug engageable in said opening, a valve member engageable with said casing seat and having a stem slidably mounted in said plug bore, said plug bore having an intermediate counter-bore, and a passage leading from said counter-bore whereby leakage from the valve casing by the valve stem will, upon entering said counter-bore, expand and pass out through said passage. 75
10. In a device of the class described, a valve casing, a valve seat in said casing in axial alinement with an opening in said casing, a centrally bored plug engageable in said opening, a valve member engageable with said casing seat and having a stem slidably mounted in said plug bore, an intermediate chamber communicating with said bore, an outer annular chamber formed by a groove in its outer periphery, passages connecting said chambers, any leakage of fluid from said valve casing by the valve stem expanding in the first mentioned chamber and then passing into said second chamber, and means for conducting said fluid from said last mentioned chamber. 80
11. In a device of the class described, a fuel supply pipe, a fuel control member in said pipe and including a valve casing, a valve member in said casing and having a stem passed outwardly of the casing through a bore therein and a pocket surrounding said stem at an intermediate point of said stem whereby fluid escaping from the valve casing around said stem will expand in said pocket, and means for conducting fluid from said pocket. 85
12. In a device of the class described, a fuel supply pipe, a fuel control member in said pipe and including a valve casing, a valve member in said casing and having a stem passed outwardly of the casing through a bore therein and a pocket surrounding said stem at an intermediate point of said stem whereby fluid escaping from the valve casing around said stem will expand in said pocket, a pilot supply pipe leading from said first mentioned supply pipe, and means for conducting fluid from said pocket to the pilot supply pipe. 90
13. In a device of the class described, a fuel supply pipe, a fuel control member in said pipe and including a valve casing, a valve member in said casing and having a stem passed outwardly of the casing through 100

a bore therein and a pocket surrounding said stem at an intermediate point of said stem whereby fluid escaping from the valve casing around said stem will expand in said pocket, a pilot supply pipe leading from said first mentioned supply pipe, the area of the opening connecting the first mentioned pipe and the pilot supply pipe being less than the area of said pilot pipe outlet 10 whereby the pressure within the pilot pipe is substantially atmospheric, and means for conducting fluid from said pocket to the pilot pipe.

14. In a thermo control device, a supporting plate, a member sensitive to temperature changes, means securing the ends of said member to said plate whereby the medial portion of the same will bow when subjected to a temperature change, one of said 20 securing means being in the form of an

adjustable element whereby the end of said member may be adjusted toward and away from the supporting plate, and said means preferably having slight play to accommodate for the expansion of the parts when subjected to heat, a heat controlling member medially connected with said temperature sensitive member whereby bowing of the first mentioned member under temperature changes will actuate the heat controlling member, and means for applying a tension to one side of the temperature sensitive member whereby the play between the parts will at all times be to one side thereof.

In testimony that we claim the foregoing we have hereunto set our hands at Milwaukee, in the county of Milwaukee and State of Wisconsin.

EMIL L. CLAUS.

WALTER E. CLAUS.
